(57) **CLAIM**

The ornamental design for an electronic visual display monitor, as shown and described.

DESCRIPTION

FIG. 1 is a front perspective view of an electronic visual display monitor showing our new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof; and,
FIG. 8 is a bottom view thereof.
The broken lines immediately adjacent to the shaded areas represent the bounds of the claim, and the remaining broken lines represent environment; the broken lines form no part of the claimed design.
